WILLIAM ROBBINS, OF HINSDALE, ILLINOIS, AND EDWARD SWASEY, OF BUCKSPORT, MAINE.

Letters Patent No. 77,097, dated April 21, 1868.

IMPROVEMENT IN AMALGAMATORS.

The Schedule referred to in these Letters Patent and making part of the same.

TO ALL WHOM IT MAY CONCERN:

Be it known that we, WILLIAM ROBBINS, of Hinsdale, in the county of Du Page, and State of Illinois, and EDWARD SWASEY, of Bucksport, in the county of Hancock, and State of Maine, have invented certain new and useful Improvements in Amalgamators; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention consists in a novel construction of a machine for washing and separating gold by the process of amalgamation, as hereinafter more fully described.

Figure 1 is a vertical section of our improved apparatus, and

Figure 2 is a perspective view of a portion detached.

The principle on which our improved apparatus operates is that of feeding the pulverized quartz, or other gold-bearing material, down into and under a column of mercury, through which it rises, and with which it is thoroughly intermingled, for the purpose of causing the particles of gold to be brought into contact with the mercury, and amalgamated therewith, and thus saved.

We construct a tub or vessel, A, of suitable size, of copper, or of wood or metal lined with copper, by preference, although this lining is not absolutely essential. Within this vessel is placed a vertical pipe or tube, B, provided at its upper end with a hopper, H, to receive the pulverized quartz and water, as hereinafter explained. This tube B is open at its lower end, which is supported on a pivot, on which it turns freely, its upper portion being supported by any suitable frame, to hold it upright.

Near its bottom, this tube B has attached to it a perforated disk, a, and it is provided above the disk with a series of radial arms, b, as shown more clearly in fig. 2. The tube B is provided with a stop-cock, d, for the purpose of shutting off and regulating the flow of material through it when desired, and has also secured to it a wheel, i, by which it is rotated. A bevel-gear, mounted on the tube B, engages with and imparts motion to a similar wheel, K, attached to the frame, L, and to a pin projecting from the face of the wheel K is connected the end of a pitman, l, the opposite end of which is jointed to the end of a rod, f, which extends vertically within the tube B to its top, where it is curved, as shown, and bent downward to meet the pitman b. To the bottom of the tub A is attached an escape-pipe, C, provided with a cock, e, as represented in fig. 1, and to the inside of the tub A, near its bottom, is secured an annular flange, c, as represented in fig. 1.

In constructing the apparatus, care must be taken to make the tube B of such a height that the column of quartz and water fed into it at H shall have sufficient hydrostatic pressure to force its way down through the mercury in the tube B, and flow out at the bottom of the tube B, from whence it will rise through the mercury in the tub, owing to the fact of its specific gravity being less than that of the mercury.

The operation is as follows: The tub A being supplied with a suitable quantity of mercury, and the apparatus being set in motion, the pulverized quartz, or other gold or other metal-bearing material, together with a current of water, is fed into the hopper H, and thence down through the tube B. As the latter revolves, the rod f prevents the material from being clogged within the tube, causing it to discharge regularly and constantly at the lower end, from whence it flows out from under the disk a, and impinges more or less against the flange c, and as it rises through the mass of mercury, it is thoroughly mixed and intermingled therewith, so as to insure bringing every particle of the gold, or other metal, into contact with the mercury, and thus save it. The gold, or other metal, being thus arrested and held by the mercury, the water and quartz rise to the top and flow away.

It is obvious that the agitator f may be detached and withdrawn at any time, and that, if it extends to the bottom, as it should, it must necessarily be withdrawn before the cock B can be closed. Motion may be imparted to the tube B by a belt, or by any suitable means.

By these improvements we are enabled to save a much larger percentage of the gold than has heretofore been possible by the various devices used, the annual loss by defective apparatus used, amounting to millions.

Having thus described our invention, what we claim is—

1. The agitator *f*, arranged to operate in connection with the tube *B*, substantially as described.
2. An amalgamator, consisting of a tub for holding the mercury, and a rotating tube provided with arms for stirring and mixing the gold, or other material, with the mercury, and having its lower open end arranged to feed the material into the mercury near the bottom of the tub, with the agitator *f* for preventing the tube from becoming clogged or choked, all constructed and arranged to operate substantially as shown and described.

WILLIAM ROBBINS,
EDWARD SWASEY.
